UNITED STATES PATENT OFFICE.

LEONARD WELDON, OF AMSTERDAM, NEW YORK.

YARN-DYEING MACHINE.

SPECIFICATION forming part of Letters Patent No. 439,708, dated November 4, 1890.

Application filed February 27, 1890. Serial No. 342,027. (No model.)

To all whom it may concern:

Be it known that I, LEONARD WELDON, of Amsterdam, in the county of Montgomery, in the State of New York, have invented new and useful Improvements in Yarn-Dyeing Machines, of which the following, taken in connection with the accompanying drawings, is a full, clear, and exact description.

This invention relates to the class of dyeing-machines which are specially designed for dyeing yarn in the skeins; and the invention consists in a novel organization of the machine, hereinafter fully described, and specifically set forth in the claims.

In the annexed drawings, Figure 1 is a side elevation of a yarn-dyeing machine embodying my invention. Fig. 2 is an end view of the same. Fig. 3 is a vertical longitudinal section on line $x-x$, Fig. 2. Fig. 4 is a vertical transverse section on line $y-y$, Fig. 1. Fig. 5 is an enlarged detail view of the connection of the yarn-supporting bar to its carrier or chain. Fig. 6 is a longitudinal section of the same, and Fig. 7 is a detached perspective view of two links of the bar-carrying chain.

Similar letters of reference indicate corresponding parts.

A represents the vat which is to contain the dye-liquor. Said vat is preferably rectangular or horizontally elongated, and lengthwise over the top thereof I extend suitable horizontal carriers supported at opposite ends of the vat, and to said carriers I connect bars $b-b$, which extend across the vat and carry the skeins of yarn suspended in the vat. For said carriers I prefer to employ endless chains $C-C$, passing around and carried taut by sprocket-wheels $D-D$, which are secured to shafts $a-a$, disposed crosswise of the vat and journaled in posts $P-P$, attached to opposite sides of the end portions of the vat and rising above the same. The lower portions of said chains between the sprocket-wheels serve as carriers of the bars $b-b$, which are angular in cross-section and pivoted to the chains, so as to allow said bars to be turned and thereby shift the skeins of yarn longitudinally thereon during the dyeing process.

To allow the skeins of yarn to be applied to and removed from the bars $b-b$, when required, I render the bars removable from the

chains by employing metallic journals c , which are separate from the bars b and have mounted on them collars d , which are adapted to slide longitudinally on the journals and grip and release the ends of the bars. By means of set-screws e , connected to the collars and engaging the journals, said collars are retained in position for holding the bars, as illustrated by full lines in Figs. 5 and 6 of the drawings.

To prevent the skeins of yarn from becoming entangled, I connect to the lower ends of the skeins suitable movable weights, preferably bars $b'-b'$, which are inserted and supported in the rows of skeins suspended from the upper bars $b-b$, and in order to maintain the suspended ends of the rows of skeins uniform distances apart and at the same time subject them to greater tension I connect to the ends of the lower bars $b'-b'$ chains $C'-C'$, which pass with their ends around the sprocket-wheels $D-D$ and are connected to the upper portions of the endless chains $C-C$. The chains $C'-C'$ hang slack from the wheels $D-D$, so as to subject the bars $b'-b'$ to the weight of those portions of the chains which are connected to them.

In order to allow all the upper bars $b-b$ to be turned simultaneously on their pivots, I fasten to the journals c star-wheels $i-i$ and mount crank-wheels $f-f$ on gudgeons secured to the side of the end portions of the vat A , and to said crank-wheels I pivot eccentrically the ends of a bar B , which is extended lengthwise of the exterior of the vat, as shown in Fig. 1 of the drawings, and is provided with teeth or projections $l-l$, adapted to engage the aforesaid star-wheels during the longitudinal movement of the bar B in one direction.

To the side of one of the crank-wheels f is rigidly attached a ratchet-wheel t , with which engages a pawl p , pivoted to a lever n , which is fulcrumed on the vat and receives an oscillatory motion by means of a cam or eccentric o , fixed to a shaft o' , which is extended across the end of the vat and is mounted in boxes or suitable bearings attached to the vat and has attached to it a driving pulley or gear I . A spring s serves to maintain said lever in contact with the aforesaid cam or eccentric. The rotation of the latter, together

with the spring, imparts an oscillatory motion to the lever, and this imparts an intermittent rotary motion to the ratchet-wheel *t* by means of the pawl *p*. The crank-wheel *f*, turning 5 with the ratchet-wheel, causes the bar *B* to receive a reciprocating motion, in the reverse movement of which the bar is carried in a plane below that in which it is carried in its forward movement, and during the latter the 10 teeth *ll* engage the star-wheels *ii*, and thereby impart to the same and to the bars *b b* a partial rotation, which causes the skeins of yarn to be shifted longitudinally on the bars, and thus carries into the dye-liquor those portions 15 of the skeins which have previously been lying on the bars *b b*.

After the dyeing process is completed the sprocket-wheels *D D* are revolved, so that the 20 portions of the chains *C C'*, which carry the yarn-supporting bars *b b'* are drawn toward one end of the vat, and as the said bars arrive 25 thereat the attendant of the machine removes them from the chains. Another set of bars with yarn hung thereon may then be connected to the chains and carried to the vat by reversing the rotation of the sprocket-wheels *D D*. Motion may be imparted to said wheels 30 by any suitable and well-known means—such as a hand-wheel *F*, attached to one of the shafts *a*, as shown.

Having described my invention, what I claim as new, and desire to secure by Letters Patent, is—

1. In combination with the vat, a series of 35 yarn-supporting bars extended across the top of the vat and distributed over the length thereof and pivoted to their supports, wheels secured to said bars, and a longitudinally-movable bar imparting rotary motion to said 40 wheels, as set forth.

2. In combination with the vat, horizontal carriers extending lengthwise of the top of the vat and supported at opposite ends of the latter, bars extending across the vat and pivoted 45 to said carriers and carrying the skeins of yarn suspended in the vat, weights movably connected to the lower ends of the skeins of yarn, wheels fixed to the pivoted upper bars, and a reciprocating bar extending 50 lengthwise of the vat and engaging the aforesaid wheels to turn the same, as set forth.

3. In combination with the vat, horizontal carriers extending lengthwise of the top of the vat and supported at opposite ends of the latter, cross-bars pivoted to said carriers and carrying the skeins of yarn suspended in the vat, weights movably connected to the lower ends of the skeins of yarn, wheels fixed to the pivoted upper bars, and a bar extending 55 lengthwise of the vat and pivoted eccentrically to rotary supports and adapted to engage and release the aforesaid wheels, as set forth.

4. In combination with the vat, horizontal 60 carriers extending lengthwise of the top of the vat and supported at opposite ends of the

latter, cross-bars pivoted to said carriers and carrying the skeins of yarn suspended in the vat, cross-bars extending through the lower ends of the skeins and supported thereby, 70 star-wheels fixed to the upper cross-bars, vertical crank-wheels on the side of the vat, a bar extending lengthwise of the vat and pivoted eccentrically to the said crank-wheels and adapted to engage and release the aforesaid star-wheels, a ratchet-wheel actuating 75 one of the crank-wheels, a pawl engaging the said ratchet-wheel, a lever connected to said pawl, and a cam and spring actuating said lever, as set forth and shown. 80

5. In combination with the vat, two sets of vertical wheels pivoted to supports on the top of the ends of the vat, endless chains extending lengthwise of the vat and carried on the aforesaid wheels, cross-bars connected 85 to the lower section of said chains and carrying the skeins of yarn suspended in the vat, and cross-bars extending through the lower ends of the skeins and supported thereby, substantially as described and shown. 90

6. In combination with the vat, two sets of vertical wheels pivoted to supports on the top of the ends of the vat, endless chains extending lengthwise of the vat and carried taut on the aforesaid wheels, cross-bars connected 95 to said chains and carrying the skeins of yarn suspended in the vat, cross-bars extending through the lower ends of the skeins, and chains supported at opposite ends on the carrying-wheels of the endless chains and having their intermediate portions slack and connected to the aforesaid lower cross-bars, substantially as described and shown. 100

7. In combination with the vat, two sets of vertical wheels pivoted to supports on top of 105 the ends of the vat, endless chains extending lengthwise of the vat and carried taut on the aforesaid wheels, cross-bars pivoted to said chains below the wheels and carrying the skeins of yarn suspended in the vat, star-wheels fixed to said cross-bars to turn the same, cross-bars extending through the lower 110 ends of the skeins, chains supported at opposite ends on the carrying-wheels of the aforesaid endless chains and having their intermediate portions slack and connected to the lower cross-bars, and a bar extending 115 lengthwise of the vat and connected at opposite ends eccentrically to rotary supports and adapted to engage and release the aforesaid star-wheels, substantially as described and shown. 120

8. In combination with the vat, a series of 125 yarn-supporting bars extended across the top of the vat and distributed over the length thereof and pivoted to their supports, star-wheels fixed to the said bars, crank-wheels pivoted to the end portions of the vat, a bar extending lengthwise of the vat and pivoted eccentrically to the crank-wheels, teeth projecting 130 from said bar and adapted to engage and release the aforesaid star-wheels, a ratch-

et-wheel secured to one of the crank-wheels, a
rotary shaft on the end of the vat, an eccen-
tric on said shaft, a lever pivoted to the vat,
a spring holding said lever in contact with
5 the eccentric, and a pawl connected to the
lever and engaging the aforesaid ratchet-
wheel, substantially as described and shown.

In testimony whereof I have hereunto
signed my name this 18th day of February,
1890.
